(57) **CLAIM**

The ornamental design for a vibrating scrubber, as shown and described.

DESCRIPTION

FIG. 1 is a side elevational view of a vibrating scrubber showing our new design;

FIG. 2 is a view of the opposite side of FIG. 1;

FIG. 3 is a top plan view of FIG. 1;

FIG. 4 is a bottom plan view of FIG. 1;

FIG. 5 is a left end elevational view of FIG. 1; and,

FIG. 6 is a right end elevational view of FIG. 1.
